UNITED STATES PATENT OFFICE.

CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

CURRENT-REGULATOR.

1,250,834.

Specification of Letters Patent. Patented Dec. 18, 1917.

Application filed June 21, 1912. Serial No. 703,011.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Current-Regulators, of which the following is a specification.

My invention relates to constant-current regulators and to systems of distribution embodying the same.

The object of my invention is to provide a constant-current regulator for use on an alternating current circuit that is of such a construction as to permit of its ready adaptation to a great variety of uses and under widely varying conditions, while, at the same time, it is simple in construction, economical to manufacture and efficient in operation, having low internal losses, especially under no-load conditions.

In its simplest form, the present regulator is employed in combination with a voltage-changing transformer, in connection with any alternating current circuit in which it is desired to maintain a constant current, such as a series of incandescent street lights, and, at the same time, effect a proper voltage transformation. When thus designed, it may supply constant current to any alternating current circuit, or to a current rectifier. When employed for supplying current to rectifiers, it may also be adapted to provide the proper amount of sustaining effect for the rectified current, as well as to supply several rectifiers at the same time either in series or in parallel. It may furthermore be readily adapted to supply different values of constant current.

Figure 1 is a diagrammatic view of a simple form of regulator that is illustrated to assist in explaining the operation of the regulator of my present invention. Fig. 2 is a view of a regulator embodying a form of my invention and adapted to effect voltage transformation. Fig. 3 is a similar view of a regulator of the kind shown in Fig. 2, but adapted to supply current to a rectifier. Fig. 4 illustrates a regulator adapted to supply constant current to a rectifier and, at the same time, to provide the proper amount of sustaining effect for the rectified current. Figs. 5 and 6 are diagrammatic views of modified forms of regulator that are adapted to supply current to a plurality of recti-

fiers, the rectifiers being connected in series in Fig. 5 and being independent in Fig. 6. Fig. 7 is a plan and sectional view, and Fig. 8 is a side and diagrammatic view of a modified form of regulator which is adapted to supply current to a plurality of parallel-connected rectifiers.

The regulator of Fig. 1 comprises a magnetizable core member 1 of any suitable form, here shown of the shell type with two movable coils 2 and 3 surrounding the middle leg thereof, the said coils having the same number of convolutions and being connected to produce fluxes in opposite directions in the core member. The movable coils are carried by cables or chains 4 and 5 that pass over sheaves or pulleys 6 and 7, respectively, one end of the chain 5 being connected to one side of the coil 2 and the other end being connected to the opposite side of the coil 3, and the chain 4 being connected in the reverse manner. The coil 2 is weighted so as to be somewhat heavier than the coil 3 in order that the said coils may be close together when no current traverses them. The coils 2 and 3 are connected in series relation and they may also be connected directly in the circuit in which it is desired to maintain a constant current such, for instance, as a series circuit of incandescent street lights 8, as indicated in Fig. 1. In this instance, a separate transformer may be employed in combination with the regulator for obtaining a suitable voltage or current transformation.

In the operation of the regulator, the coils 2 and 3 will be closely adjacent when the effective impedance or back electromotive force of the load is highest, but for intermediate values of these quantities they will occupy positions such that the current will be maintained constant with varying load reaction or back electromotive force, or, in other words, the virtual impedance of the primary circuit is maintained constant by the repulsion of the coils for all values of the load impedance or back electromotive force. Consequently, at light loads the coils will be far apart, and at heavy loads close together. When the coils are close together, very little induction passes through the middle core leg, whereas, when they are most widely separated, the induction in the middle leg is comparatively large.

Where it is necessary to employ a trans-

former for effecting the proper voltage or current transformation, it is desirable, for the sake of economy, to combine the means for effecting such transformation with the regulator. This is done in Fig. 2, in which the middle leg of the magnetizable core is surrounded by primary and secondary coils 10 and 11 which are placed in close inductive relation and are employed for the purpose of effecting voltage transformation, current being supplied from the secondary winding to any suitable circuit 12, such as a series of lamps. The middle core leg is also surrounded by the movable regulator coils 13 and 14 the same as in Fig. 1, the said coils being connected in series with the primary coil 10 and being otherwise connected and arranged as in Fig. 1. The coils 10 and 11, being in close inductive relation, the desired voltage transformation will be efficiently obtained while, at the same time, the movable regulator coils 13 and 14 will introduce the proper reactance into the primary circuit for the purpose of maintaining the current in the secondary circuit substantially uniform.

It is important, in order to insure efficient operation of the regulator, that the two movable coils 13 and 14 be connected in series circuit with the primary coil 10 of the potential transformer. Under no-load conditions, the movable coils 13 and 14 are separated from each other the maximum distance, and the entire potential drop in the primary circuit is consumed in overcoming the impedance of the two movable coils because, in this position, the leakage reactance between the coils reaches its maximum value. In consequence thereof, the leakage flux passes from the central core leg between the two coils, divides into two paths and flows in opposite directions in the outer core legs of the core member. As a result, the core is uniformly magnetized to a low degree which insures efficient operation of the regulator, or, in other words, very low no-load losses. If one of the movable coils were connected in circuit with the primary winding and the other in circuit with the secondary winding, as has been heretofore proposed, the primary winding, under no-load conditions, would divide the potential of the line, with the movable coil connected in circuit with it, and, consequently, an uneven flux distribution in the core member would obtain, subjecting portions of the core member to a very high degree of magnetization and other portions to a relatively low degree of magnetization. The uneven flux distribution within the core would increase the no-load losses appreciably.

In Fig. 3, a regulating and transforming device similar to that of Fig. 2 is employed for the purpose of supplying a constant amount of current to a current-rectifying

device 15, here shown as of the mercury vapor type, though any other suitable form may be employed. In this device, the secondary winding comprises four coils 16, 17, 18 and 19, respectively, two surrounding the upper end of the middle leg of the core and two the lower end thereof, the primary coils 20 and 21 being interposed between the two secondary coils at each end of the leg of the core and extending from end to end thereof. The object of this arrangement of the coils is to separate from each other the secondary coils that supply alternate half waves of current to the rectifier, so as to reduce the mutual induction, and to thereby provide for a large amount of leakage, between the coils. This leakage takes the form of a pulsating inductional flux, its effect being to introduce inertia into the system, similarly to a fly wheel in a mechanical system. In order to provide for a greater sustaining effect for the rectified current, it is also desirable to employ a reactance device 22 in series with the load that is supplied from the rectifier.

Another form of the device that is adapted to supply current to a current-rectifying device is shown in Fig. 4, in which only the movable regulator coils 24 and 25 surround the middle leg of the core member, and the outer legs are respectively surrounded by primary coils 26 and 27 and secondary coils 28 and 29, the primary coils being connected in series with each other and with the regulator coils 24 and 25, as in the previously described devices. The anodes of a current-rectifying device 30 are respectively connected to terminals of the secondary coils 28 and 29 and the cathode is connected to the remaining terminals thereof.

With this form of the device it is unnecessary to employ an additional impedance device for the purpose of sustaining the rectified current, since the desired amount of reactance is provided in the transformer itself. This will be understood from a consideration of the directions of the fluxes produced by the currents traversing the several coils. The primary coils 26 and 27 produce fluxes in the core member that are supplementary or traverse it in the same general direction, as indicated by the broken lines 31, the said fluxes having the direction indicated by the arrows 32 for alternate half cycles of the alternating current and the direction indicated by the arrows 33 for the other alternate half cycles. When the flux in the core has a direction indicated by the arrows 32, the secondary coil 28 is active and the primary flux is opposed by the counter-flux of the said secondary coil, which is indicated by the broken lines 34 which has a direction indicated by the arrows 35. During the next half cycle, the secondary coil 29 is active and the primary flux, which is

indicated in direction by the arrows 33, is opposed by the counter-flux indicated by the broken line 36, which has a direction indicated by the arrows 37. It will be noted 5 that the counter-fluxes indicated by the broken lines 34 and 36 traverse the central leg of the core in the same direction. The effect of this unidirectional flux is the same as that due to the introduction of inductance 10 into the direct current circuit of the rectifier, that is to say, it introduces inertia into the system whereby the current pulsations are reduced to a small value. This reactance is adjusted to the proper value by providing 15 the central leg of the core member with an air gap indicated at 38. The provision of this air gap does not impair the regulation afforded by the movable coils 24 and 25, since the fluxes produced by the said coils oppose 20 each other, and consequently, they are not effective to send flux through the magnetic circuit in the same direction. As in the preceding regulators, the flux due to the regulator coils 24 and 25 is low when the 25 load is high, and, under such conditions, the middle leg of the core will be traversed substantially only by the sustaining flux. Since the sustaining flux always traverses the middle leg of the core in the same direction, 30 it first supplements and then opposes the working flux in the core, the result through a whole cycle being the same as if the regulator coils were not employed at all.

It will, of course, be understood that, if 35 desired, each half of the secondary winding may be divided into two or more parts and may comprise two or more coils, which may be connected in series or in parallel relation for the purpose of adapting the device to 40 supply different amounts of current, or for the purpose of permitting the employment of the device in connection with two or more current rectifiers. The manner in which the device will be constructed for such pur- 45 poses and in which the connections should be made will be readily understood from the manner in which transformers are usually constructed and connected for similar purposes, and it is, consequently, deemed un- 50 necessary to illustrate the same.

When current is to be supplied to a plurality of current rectifying devices, I prefer to construct the regulating and transforming device as illustrated in Figs. 5 and 6, in 55 which the core member is provided with a central leg 40 and a plurality of outer legs 41, 42, 43 and 44, the central leg being surrounded, as usual, by the movable regulator coils 45, and each of the outer legs being 60 surrounded by primary and secondary coils 46 and 47, respectively. The primary and secondary coils may be connected in many suitable and practical arrangements, but, in Fig. 5, the primary coils surrounding the 65 legs 41 and 43 are connected in series, and

also the primary coils surrounding the legs 42 and 44, and the two series-connected pairs of coils are connected in parallel relation and in series with the regulator coils 45. The connections of the rectifying devices to 70 the secondary coils are such that the rectified current passes through the rectifying devices in series. To this end, the anodes of the rectifier 48 are respectively connected to terminals of the secondary coils surrounding 75 the core legs 41 and 43, and the anodes of the rectifier 49 are respectively connected to terminals of the secondary coils surrounding the legs 42 and 44, while the cathode of the device 48 is connected to the remaining 80 terminals of the coils surrounding the legs 42 and 44, and the cathode of the device 49 is connected to the remaining terminals of the coils surrounding the legs 41 and 43, the translating devices to which the current is 85 supplied being preferably included in the latter connection. In some instances, it may be desirable to provide the middle leg 40 of the core with an air gap.

In Fig. 6, the primary coils are all connected in series relation and in series with the movable regulator coils, and current is supplied from the secondary coils to two independent rectifying devices 50 and 51, each supplying its own circuit. The secondary 90 connections are similar to those of Fig. 5, except that the cathodes of the rectifiers are connected through the translating devices to the remaining terminals of the same secondary coils as those to which their anodes 100 are respectively connected.

In Figs. 7 and 8, a modified form of a regulating transformer is shown similar to that of Figs. 5 and 6 but adapted to provide a large amount of inductance opposed to the 105 flow of current in the rectifiers upon the occurrence of short circuits therein. The general form of the core member is similar to that of Figs. 5 and 6, but comprises four 110 similar rectangular portions each comprising two legs, and each similar in shape to the core of a core-type transformer. The four core portions are placed with one leg of each adjacent as shown in Fig. 7, to form an assembled core having a middle leg and four 115 outer legs, the middle leg being surrounded by the movable regulator coils.

The coils 52, 53, 54 and 55, which surround the outer legs of the core, are connected in series in pairs, one pair comprising 120 the coils 52 and 55, and the other pair comprising the coils 53 and 54. Both pairs are then connected with each other in parallel relationship and in series with the regulator coils. This form of connection is similar to 125 that shown and described in detail in connection with Fig. 4 where one pair of coils only is connected in series with the regulator coils. One terminal of each of the secondary coils 56 and 57, which are simultaneously 130

influenced by the divided currents flowing in the coils 52 and 53, respectively, are connected to the respective anodes of the current rectifier 60, the other terminal of each 5 of said secondary coils being connected, through the lamp circuit 62, to the cathode of the rectifier 60. Similarly, one terminal of each of the secondary coils 58 and 59, which are simultaneously influenced by the 10 divided currents flowing in the coils 54 and 55, respectively, are connected to the respective anodes of the current rectifier 61, the other terminal of each of said secondary coils being connected, through lamp circuit 15 62, to the cathode of the rectifier 61. The coils are so wound that the magnetic fluxes generated by the secondary coils 56 and 59 during one alternation, and the coils 57 and 58 during the other alternation of the primary 20 current wave, flow through the middle leg of the core in the same direction. The effect of this unidirectional flux through the core leg embraced by the regulating coils is the same as that which obtains by introducing 25 an inductive-reactance element in the direct-current circuit of the rectifier, as explained in connection with the device of Fig. 4. To obtain further sustaining effect, two impedance devices 63 are connected in 30 the leads extending from the cathodes of the rectifiers. If, with this arrangement of connections, a short circuit occurs in the rectifier 60, for instance, the short circuit current will traverse secondary coils 56 and 57 and 35 induce currents in the corresponding primary coils. The current induced in the primary coil 53 is thus combined with the current in the primary coil 52 to produce a distortion of the wave form of the primary 40 current. This gives the effect of a high inductance in each branch of the parallel connection in series circuit with the regulator coils, thereby limiting the flow of the short-circuit currents.

45 I claim as my invention:

1. A regulator comprising a core, primary and secondary windings thereon, and movable coils surrounding a part of said member and connected in series with the primary winding.
2. A regulator comprising a core, primary and secondary windings thereon, and movable coils surrounding a part of said member and connected in opposition to each 50 other and in series with the primary winding.

3. A regulator comprising a core, primary and secondary windings thereon, movable coils surrounding a part of said member and connected in series with the primary 60 winding, and counterbalancing means for the movable coils.

4. A regulator comprising a core, primary and secondary windings thereon, movable coils surrounding a part of said member 65 and connected in opposition to each other and in series with the primary winding, and means for causing the movable coils to move simultaneously and correspondingly.

5. A regulator comprising a core, primary 70 and secondary windings thereon, and movable coils having substantially equal numbers of convolutions surrounding a part of said member and connected in opposition to each other and in series with the primary 75 winding.

6. A regulator comprising a core member having a central leg and a plurality of outer legs, primary and secondary coils upon the outer legs, and movable coils upon the central leg that are connected in series-circuit 80 relationship with said primary coils.

7. A regulator comprising a core member having a central leg and a plurality of outer legs, primary and secondary coils upon the outer legs, and movable coils upon the central leg connected in opposition to each other and in series with the primary coils.

8. A regulator comprising a core member having a central leg and a plurality of outer 90 legs, a primary coil and a secondary coil upon each outer leg, and movable coils upon the central leg connected in opposition to each other and in series with the primary winding.

9. A regulator comprising a core, primary and secondary windings thereon, two movable coils surrounding a portion of said core and having substantially equal numbers of convolutions, the said coils being connected 95 in series and in opposition to each other and in series circuit with said primary winding, and means for causing the said coils to move simultaneously and correspondingly.

In testimony whereof, I have hereunto 105 subscribed my name this 18th day of June, 1912.

CHARLES LE G. FORTESCUE.
